UNITED STATES PATENT OFFICE.

GEORGE W. BURKE, JR., OF DAYTON, OHIO.

FIRE EXTINGUISHER.

Application filed October 7, 1922. Serial No. 593,034.

The object of this invention is to provide a fire extinguisher of the type disclosed in my patent application No. 428,006, filed December 3, 1920, with a swivel valve so as to 5 permit all of the liquid in the extinguisher to be used.

A second object is the provision, within the end of the extinguisher, of a pressure gauge so that the same is shielded by the 10 end of the extinguisher itself, from any blows which it might be subjected to.

Further objects are to provide suitable bearings for the swivel valve within the extinguisher, to provide a means for conducting 15 the fire extinguishing fluid from the swivel valve to a side discharge opening, and to provide a new and improved valve closures for the ends of the valve tube.

Other objects and advantages will be more 20 fully set forth in the attached specification and claims.

In the drawings:

Figure 1 is a part sectional side elevation of the fire extinguisher.

25 Figure 2 is an end view of the same.

Figure 3 is a section on line 3—3 of Figure 1 on an enlarged scale.

The fire extinguisher is provided with a main fluid container 1, having at one end a 30 valve 2 through which the fire extinguishing liquid is supplied to the container. A hand-grip 3, trigger mechanism 4 and discharge valve 5 are attached to the side of the container, so as to permit the device to be 35 grasped, aimed, and operated by a single hand of the operator. One end of the container is closed by an end cap 6 which is adapted to be pressed inside of the end of the container shell. End cap 6 supports a bushing 7 within which is screwed the valve 8 of 40 a pressure gauge 9. The pressure gauge is protected by the cap and the end walls of the container from any shocks which it would otherwise be subjected to.

45 The bushing 7 has projecting arms 10 which support a bearing member 11 provided with adjusting screw 12. At the opposite end of the container and at the side thereof is a discharge opening 13, within 50 which is suitably brazed or welded a T shaped casting 14, one side of the T head extending out through the end of the con-

tainer and supporting the valve 2 while the other side of the T head rotatably supports a casting 15 which is rigidly connected to a 55 longitudinally extending tube 16 near one end of the same. Seventeen (17) is a hollow supporting tube which is rotatable, mounted at one end in the bearing 11 and at the other end is rigidly mounted in the 60 casting 15, as shown. Tube 16 is connected at one end to the supporting tube 17 by a strap 18 and is connected at the center by a second strap 19. Weights 20, 20 may be supplied to the tube 16, if desired, to always 65 keep the tube at the lowest position within the casing.

Each end of the tube 16 is adapted to be closed by a valve closure 21 which preferably has a semispherical face 22 and rearward extensions 23. These extensions are guided by projecting fingers 24 on the tube 16, and the two valve closures are connected by a rod 25 so that when one end of the tube is open the other end will be tightly 75 closed.

After the fire extinguisher has been nearly filled with the extinguishing liquid through valve 2 the inside of the casing is put under pressure by supplying gas under pressure 80 through the same valve until the pressure gauge registers the desired amount. By operating the trigger so as to open the valve mechanism 5 the compressed gas within the casing forces the liquid through the open end 85 of the tube 16, through castings 15 and 14 and then out of the discharge opening. If the extinguisher should have only a very small amount of liquid therein and it is aimed upwardly, the weight of the valve 90 closures 21 and rod 25 will cause the upper end of the tube 16 to be closed and the lower end open. If the extinguisher should now be turned upside down, the tube 16 will be acted upon by gravity and will at this time move 95 around, due to its free suspension, so as to be opposite the handle and thus make it possible to use practically all of the liquid regardless of the position of the extinguisher.

Having thus set forth the preferred embodiment of my invention, what I desire to 100 secure and claim by Letters Patent is:—

In a fire extinguisher, a cylindrical fluid container, a discharge opening near one end

thereof, a cylindrical tight fitting end piece open at the rear end for closing the rear end of the container, and having a pressure gauge enclosed therein flush with the rear end 5 thereof, a pipe extending inwardly from the discharge opening, a swivel valve comprising a tube and valve closures therefor, means

for mounting said tube on the pipe and end closure, a laterally extending pistol grip extending from a side of the container near the center thereof and a finger operated valve adjacent thereto for controlling the discharge of fire extinguisher fluid.

GEORGE W. BURKE, JR.
